UNITED STATES PATENT OFFICE

CHARLES D. OTTO, OF NEW YORK, N. Y.

LUBRICATING DEVICE

Application filed April 22, 1926. Serial No. 103,879.

This invention appertains to a lubricating device.

One object of my invention is to produce a system of forced lubrication in which the parts to be supplied with the lubricant under pressure are fed from the oil supply of a hydraulic pressure compensation mechanism of a briquetting press.

Another object of my invention is to provide means between the pressure source of lubrication supply and the discharge point of same by which the amount of the supply may be regulated.

Another object of my invention is to provide means between the pressure source of lubrication supply and the discharge opening of same by which the amount of pressure under which the lubricant is discharged may be controlled.

Another object of my invention is to provide a briquetting press in which the pressure applying mechanism is mounted upon a liquid supported base the pressure in which is maintained by a flexible element such as steam and using the pressure maintained on the fluid element to force a part of the fluid element between the friction surfaces of the briquetting compacting pressure applying mechanism.

Another object of my invention is to provide a system of lubrication in which the lubricant supply is maintained at a constant pressure throughout a major portion and at a greater pressure during the additional portion of the machine cycle.

Another object is to provide means by which the amount of lubricant supplied under pressure at each individual point of discharge may be controlled.

In the accompanying drawings—

Figure 1 is a sectional view through the center of a briquetting press such as is used in the manufacture of asphalt paving blocks, showing the parts in non-pressure applying position.

Figure 2 is a similar view to Figure 1 showing the mechanism in pressure applying position with the hydraulic supporting piston partly depressed.

Figure 3 is a section perpendicular to

the section shown in Figure 1 showing parts in position when the cam is 90° from that in Figure 1.

This press is similar to the one described in Patent Number 1,128,309, dated February 16, 1915, and granted to Garabed G. Heghinian.

The horizontal driving shaft 1 is mounted in standards 44, 45 and 46, and this shaft 1 carries a worm wheel 42 engaging a worm 41 which is driven in some suitable manner from some suitable source of power. A top cross head 4 and a bottom cross head 5 are united by groups of heavy vertical slide bars 6 on which cam rollers 9 are mounted, one on each side of the machine, said cam rollers each running on the edge of a cam 10 secured on the shaft 1, so that as the shaft 1 revolves, the cross heads 4 and 5 are moved up and down in unison.

An anvil 12 provided with flanges 14 rests by means of said arms on the standards 45 and 46 and can be forced upward by the cam 13 on the shaft 1 which cam can act on a roller 43 in the lower part of the anvil. The anvil fits into and is adapted to move upward into the die or mold 48 directly beneath and in line with the compressor head 18 formed on the lower end of the upper cross head 4. On the top of the mold 48 a box 19 is mounted to slide horizontally and is provided with an opening of the same size as the top of the anvil 12 and compressor head 18, said box being slidable to and fro in proper frequency and sequence by mechanism not shown, but described in Patent Number 1,128,309.

The lower cross head 5 comprises a cylinder into which is placed a plunger 22 which, of course, is provided with the usual hydraulic packings which have been omitted for clearness. This plunger is provided with lateral projections which pass into the corresponding internal grooves in the cylinder 5, which grooves are of such height as to give the plunger a certain up and down play in the cylinder. The top of the plunger is connected with toggles 17 pivoted to the frame of the machine and to a guided vertically movable member 15 which carries at its upper end the

roller 16 upon which the cam can act. The interior of the cylinder 5 communicates by the channel 24 with the steam cylinder 29 by means of pipes 24 and 25.

U-shaped latches 11 are provided and pivoted at 53 to the vertical bars 6 and by springs surrounding the pivots of said latches, the upper free end of the latches thrown inward and into that path of the flanges 14 of the anvil 12, said flanges being provided with a bevel at the bottom corner of the outer end for a purpose that will be set forth.

The cylinder 23 has the part 24 flexedly connected to the high pressure line 25 which connects with the bottom of the cylinder 26 which has slidably mounted therein the piston 27. This piston carries at its upper end the piston 28 which is free to travel in the cylinder 29. In tapped holes in the top of this cylinder are mounted the safety or blow off valve 30, the gauge 31 and the steam inlet pipe 32.

The high pressure oil pipe 25 is tapped between the oil cylinder 23 and the steam cylinder 26 at the point 33. The branch pipe 34 on which is mounted the pressure reduction valve 35 and the reducing valves or cock 36. The header or manifold 37 has tapped into it the branch lines 38 which are provided with the additional controlling cocks 39. Where necessary the flexible connections 40 are provided to allow for the travel of the parts. The header is joined to individual distributing pipes 40 as shown and which are connected to shafts or pins 17' of the toggle joints 35 and by 40^a to direct lubricant on the surface of cam 13 as shown in Fig. 1. The shafts and bearings being drilled and grooved in a suitable manner to allow a proper distribution of the lubricant. The shafts or pins move in 40 their respective bearings and the lubricant is fed to the bearings so as to lubricate and reduce the friction between the shaft or pins and its bearing.

The operation is as follows:

The empty box 19 is passed under the hopper 47 and the plastic or semi-plastic material such as asphalt filled into said box which is then removed from under the outlet chute of the hopper 47 beneath the compressor head 18 of the upper cross head 4. The anvil now rests upon the upper end of the standards 45 and 46, the upper end of the anvil closing and fitting into the lower end of the mold 48. The cam 13 through the toggle levers forces down piston 22, the lower cross head 5 and also the upper cross head 4, causing the compressor head 18 at the same to force the charge of asphalt from the box 19 into the mold 48 and upon the upper end of the anvil 12. Then both the cross pieces are raised under the action of the cams 10. With the parts in the position as shown in Figure 3 the block has just been molded and is within the mold above the top of the anvil 12. By the action of the box

actuating mechanism box 19 is now rapidly withdrawn and brought beneath the chute of the hopper 47 and filled with fresh material and the cam 13 now forces up the anvil which pushes the completed block up to the level of the top of the mold, as is shown in Figure 1.

As the anvil rises, the latches 11 are first pressed outward and then snap inward and engage the bevels in flanges 14 of the anvil, and thus hold the anvil in raised position, it being, of course, understood that during this time the bars 6 and their top and bottom cross heads are in extreme raised position. By the action of the mechanism not shown, the now filled box 19 is brought into the positions shown in Figure 3 and pushes the completed block to the left on the top of the mold and the completed block is removed. The cam 13 now acts on the bottom roller 16 and forces the same down whereby the bars 6 and top and bottom cross heads are forced down, the cams 10 being so shaped as to permit of this.

The compressor head 18 on the top cross head now forces the material in the box through the box 19 and into the mold and upon the upper end of the anvil which is still raised. As the compressor head 18 descends, the latches 11 and blocks 8 descend with it, and come in contact with the outer sides of the standards 45 and 46, are pressed sidewise thus releasing the anvil just before it comes to a position of rest with its flanges 14 on the standards 45 and 46, and the intervening charge of asphalt is now compressed in the mold between the top of the anvil 12 and the bottom of the compressor head 18, and now the cams 10 begin to act and lift up the bars 6 and the top and bottom cross heads and bring them into position shown in Figure 3 and so on.

The steam is admitted to the cylinder 29 at a predetermined pressure which is indicated on the gauge 31, and if the blow off valve 30 is then set to operate at a pressure slightly above that indicated on the gauge 31, it will be readily understood that as the toggles apply a downward pressure to the top of the piston 22 that is greater than the upward pressure of the oil on the piston, the pressure in the steam cylinder 29 jumps upward in pressure and the poppet valve 30 opens until the pressure has again dropped to the original reading when this occurs "and it occurs at the end of each downward compression stroke of the press." The pressure in the oil line 25 has for the same period of time or part of the machine cycle also proportionately increased in pressure and then returned to normal. If, however, the poppet valve is set at a pressure somewhat above the gauge pressure, i. e. at the maximum allowable pressure for the press, the downward pressure of the oil piston will be transmitted to the steam but the steam valve will not go off unless the safe pressure is exerted. Thus

as the pressure in the oil cylinder mounts the pressure in the steam cylinder mounts proportionately due to the compression of the steam and as the oil piston releases the pressure, the steam pressure returns to normal. The poppet valve will not go off unless due to some obstruction or a super-normal charge, etc. the press develops as dangerous pressure at which time the poppet valve will go off to release that pressure.

There is a quantity of oil at high pressure in the line 25. This pressure can be proportionately reduced at the valve 35, and the quantity controlled collectively by the cock 36 on the main line and individually by the cocks 39 on the branch lines. The flow of oil under a predetermined pressure, i. e. that controlled by steam pressure, and in a predetermined quantity is being fed to the surface 20 of cam 1, the bearings in which shaft or roller 16, shafts 17' of toggle 17 during the greatest part of the machine cycle but at the time when the machine has reached its maximum pressure and consequently while the bearing parts are in greatest frictional contact, the pressure to all of the points being thus lubricated is during this period raised to a higher pressure and greater volume and which is of course desirable at this time.

30 Thus as the piston head descends due to the pressure of the toggles the work done increases due to the compression of the briquette. The downward movement of the oil friction increases the pressure on the oil and causes a consequent upward travel of the steam cylinder. This compresses the steam up to a predetermined point beyond which the steam valve opens. This fixes the upper possible limit of developed pressure. The variation of oil pressure and consequently the pressure and volume of oil passing to the lubricated parts varies with the work done by these parts.

45 The volume of oil in the hydraulic cylinder is sufficiently great so that the amount of oil used in lubrication does not affect the operation, since the reduction in volume merely causes the lowest position of the steam piston to be lowered. It is but necessary to pump additional oil intermittently into the system as by pump 49.

Various modifications of the above may be utilized such as the introduction of additional pressure regulating valves on each of the feed lines 38. Also the pressure may be obtained from other points than that illustrated.

55 The above description is not to be taken as limiting of my invention, which I claim to be:

60 1. A lubricating apparatus comprising in combination, a movable member, a second member adapted to engage said movable member in frictional relationship along a surface of frictional contact, means for rela-

tively moving said members to impose a variable load on said surface of frictional contact and means for feeding said lubricant to said surface of frictional contact in accord with said variable load.

70 2. A lubricating apparatus comprising in combination, a movable member, a second member adapted to engage said movable member in frictional relationship along a surface of frictional contact, means for relatively moving said members to impose a variable load on said surface of frictional contact, means for feeding lubricant under pressure to said surface of frictional contact and means for varying the pressure in accord with said variable load.

75 3. In a lubricating apparatus in combination, a plurality of movable members, means for engaging certain of them in frictional contact along the surface of frictional contact, means for imposing a load on said members in a direction at an angle other than 180° to said frictional surface, means for varying said load to vary the friction on said surface of frictional contact and means for forcing 80 lubricant to said frictional surface in accord with said variable friction on said frictional surface.

85 4. A lubricating apparatus comprising in combination, a rotatable member a second member adapted to engage said rotatable member along a surface of frictional contact, means for rotating said first member, means for imposing a variable load on said rotatable member, means for feeding lubricant to 90 said rotating member in accord with said load on said first member.

95 5. In combination, a mold, an anvil operating in said mold, means for actuating said anvil, comprising a toggle, a cam operatively connected to said toggle, means for actuating said cam and means for feeding lubricant to 100 said toggle and said cam in accord with the load.

105 6. In combination, a briquetting press, standards, an upper crosshead, a lower crosshead, means for actuating said crossheads, comprising a cam, a roller, a toggle pivotally connected to said standards and to said roller, means for feeding lubricant to 110 said roller and to the joints of said toggle in accord with the load on said toggle and said roller.

115 7. In combination, a cylinder, a piston, a substantially incompressible fluid medium in 115 said cylinder, means for applying a pressure to said piston, means for limiting the maximum pressure developed in said cylinder, means for feeding the lubricating medium under a pressure responsive to the pressure developed in said cylinder.

120 8. In combination, a cylinder, a piston, a compressible means for applying pressure to 125 said piston, a second piston, a cylinder for said second piston, means for applying a 130

pressure to said second piston, a substantially incompressible lubricating fluid adapted to transmit the pressure developed in said second piston to said first mentioned piston, 5 means for by-passing a portion of said lubricant, means for transmitting said by-passed lubricant to parts to be lubricated thereby.

9. In the combination claimed in claim 8, means for limiting the maximum developed 10 pressure in said first mentioned cylinder.

10. In combination, a cylinder, a piston, a compressible means for applying pressure to said piston, a second piston of lesser diameter than said first piston, a cylinder for said 15 second piston, said second piston being operatively connected to said first mentioned piston, a third piston, a cylinder therefor, said third piston being operatively connected to said second piston through the medium of a substantially incompressible lubricating 20 material, a port in said second cylinder, a port in said third cylinder, connecting means between said ports, a by-pass located in said connecting means, means containing frictional parts for applying a load to said third piston, and connections from said by-pass to certain of said frictional parts.

11. In the combination claimed in claim 10, means for regulating the maximum pressure applied to said first mentioned piston.

12. In combination, a shaft, a bearing for said shaft, means for moving said shaft on said bearing, means for imposing a variable load on said rotating shaft and means for 35 feeding lubricant to said bearing in accord with said load.

13. In combination, a shaft, a bearing for said shaft, means for moving said shaft on said bearing, means for imposing a variable 40 load on said rotating shaft, means for feeding lubricant under pressure to said bearing and means for varying the pressure of said lubricant in accord with said variable load.

14. In combination, frictional surfaces 45 operating under load in a cycle of operations, first under a low load and then under a high load, means for feeding lubricant under pressure to said frictional surfaces, means for increasing the pressure on said lubricant in 50 accord with said cycle of operation, the pressure on said lubricant being high when the load is high, and low when the load is low.

In testimony whereof I affix my signature.
CHARLES D. OTTO,
